ABRAHAM K. SANDERS, OF BROOKLYN, ASSIGNOR TO HIMSELF AND JOHN H. BURTIS, OF NEW YORK, N. Y.

Letters Patent No. 77,325, dated April 28, 1868.

IMPROVEMENT IN HEATER-RANGES.

The Schedule referred to in these Letters Patent and making part of the same:

TO ALL WHOM IT MAY CONCERN:

Be it known that I, ABRAHAM K. SANDERS, of Brooklyn, in the county of Kings, and State of New York, have invented, made, and applied to use a certain new and useful Improvement in Cooking-Ranges; and I do hereby declare the following to be a full, clear, and exact description of the said invention, reference being had to the annexed drawing, making part of this specification, wherein—

Figure 1 is a vertical section, transversely, of the range at the line *x x*.

Figure 2 is a vertical longitudinal section, at the line *y y*; and

Figure 3 is a sectional plan, at the line *z z*.

Similar marks of reference denote the same parts.

The object of this invention is to supply warm air to rooms above the range, when the range is not otherwise in use, or to direct the heat to the ovens and parts for cooking, and only allow the waste heat to be operative in heating a current of air in its passage to the room or rooms above.

The nature of my invention consists in an arrangement of flues, passing from the fireplace to a heating-chamber, around which flues and chamber a current of air to be warmed passes, and I arrange dampers in such a manner as to direct the heat of the fire to the ovens and cooking portion of the range, and the heat that passes from them enters the aforesaid heating-chamber, so that the range may be employed for cooking purposes to its fullest capacity, and any surplus heat be employed for warming a current of air to pass into the rooms above, or when the range is not employed for cooking, the heat of the fire is availed of entirely for heating said current of air.

In the drawing, *a* represents the lower portion of the range, with the fireplace *b* and top *c* for the reception of pots and other cooking-utensils, as usual. This portion of the range is built into a fireplace, with air-spaces on each side, formed in brick-work or of metal plates. I have shown the metal plates without the brick-work, the same forming air-spaces, *d d*, on each side of the range, opening at the lower part for the cold air to pass in.

The top of the range is connected with the bottom part of the elevated oven-ease, *e*, by the metal plates *f*, in the angles of which the flues, *g*, pass up from the fire to said oven-ease *e*.

The ovens, *h h*, are fitted in the usual manner to slide into the case *e* from the front, and are provided with doors, but I introduce a plate, *l*, between the upper outside angle of the oven and the case *e*, and I place deflecting-plates, *2* and *3*, in the flue on the opposite side of the oven, as seen in fig. 2, to direct the products of combustion towards the front of the oven, and insure the more uniform heating of the same. The products of combustion pass over the ovens in the flue *4*, thence through the flues *5* and *6* to the ascending-flue, *i*, to the heating-chamber *k*.

l l are chambers for warming plates, or for any similar domestic uses.

m is a damper, that opens into the oven-ease, near the front and bottom edge thereof, to take off the vapors and smell from the articles being cooked on the body of the range.

At each side of the lower portion, *a*, of the range are flues *n n*, with dampers *7*, leading to the vertical range of flues *o o* that extend up to the chamber *k*, and in this chamber *k* horizontal plates, *8* and *9*, direct the products of combustion back and forth, so as to detain them sufficiently to cause them to heat the plates forming such chamber before passing away by the flue *p* to the chimney.

It will now be seen that the dampers *7* can be opened when the fire is being kindled, and give the most direct draught, and at the same the air in the chamber or spaces *d d* is being warmed, and passes off through a tube, *q*, to the room or rooms above.

When the dampers *7* are closed, the heated products of combustion all pass into the oven-ease, and, by the dampers *10* and *11*, may be directed to either or both ovens. By the damper *12*, at the junction of the flues *5* and *6*, the fire may be checked, if desired, by partially closing the draught-space and opening a cold-air inlet from the front plate. This damper has before been used in this connection and for this purpose.

If desired, part of the products of combustion may be directed through the range of pipes, *o o*, on one side, while a portion of the heat passes up to one of the ovens, the dampers giving complete control of the direction in which the heat is to travel, and its intensity either in heating a current of air for warming purposes, or in effecting baking, boiling, or other culinary operations.

What I claim, and desire to secure by Letters Patent, is—

1. The arrangement of the flues *o o* and dampers *7*, at the sides of the range, in the air-spaces *d*, in combination with the flues *g*, to the ovens *h h*, as and for the purposes specified.
2. The heating-chamber *k*, provided with the plates *8* and *9*, in combination with the flues *o o*, *i*, and *p*, and ovens *h h*, the parts being arranged and operating in the manner and for the purposes set forth.

In witness whereof, I have hereunto set my signature, this twenty-fourth day of May, A. D. 1867.

A. K. SANDERS.
